(57) **CLAIM**

The ornamental design for a dialysis fluid line carrier, substantially as shown and described.

DESCRIPTION

FIG. 1 is a perspective view of a dialysis fluid line carrier to which various dialysis fluid lines and related components can be secured.

FIG. 2 is a front plan view of the dialysis fluid line carrier of FIG. 1.

FIG. 3 is a rear plan view of the dialysis fluid line carrier of FIG. 1.

FIG. 4 is a first side view of the dialysis fluid line carrier of FIG. 1.

FIG. 5 is an opposite, second side view of the dialysis fluid line carrier of FIG. 1.

FIG. 6 is a top view of the dialysis fluid line carrier of FIG. 1.

FIG. 7 is a bottom view of the dialysis fluid line carrier of FIG. 1.

FIG. 8 is a perspective view of a dialysis fluid line set that includes various dialysis fluid lines and components secured to the dialysis fluid line carrier of FIG. 1. The various fluid lines and components are shown in dashed lines as a representation of environment and are not elements of the claimed design.

FIG. 9 is a front plan view of the dialysis fluid line set of FIG. 8.

FIG. 10 is a rear plan view of the dialysis fluid line set of FIG. 8.

FIG. 11 is a first side view of the dialysis fluid line set of FIG. 8.

FIG. 12 is an opposite, second side view of the dialysis fluid line set of FIG. 8.

FIG. 13 is a top view of the dialysis fluid line set of FIG. 8.

FIG. 14 is a bottom view of the dialysis fluid line set of FIG. 8; and,

FIG. 15 is a front plan view of the dialysis fluid line set of FIG. 8 secured to a dialysis machine during use. The dialysis machine, like the various dialysis fluid lines and components, is shown in dashed lines as a representation of environment and is not an element of the claimed design.
